UNITED STATES PATENT OFFICE.

LEWIS S. CHICHESTER, OF JERSEY CITY, NEW JERSEY, ASSIGNOR TO C. M. EDWARD SCHROEDER, OF SAME PLACE.

PULVERIZING-MACHINE.

SPECIFICATION forming part of Letters Patent No. 295,617, dated March 25, 1884.

Application filed December 29, 1882. Renewed December 27, 1883. (No model.)

To all whom it may concern:

Be it known that I, LEWIS S. CHICHESTER, of Jersey City, in the county of Hudson and State of New Jersey, have invented certain new and useful Improvements in Pulverizing-Machines, of which the following is a specification.

This invention has reference to an improved machine for pulverizing or reducing hard substances—such as fertilizers, minerals, cereals, and other substances—to any desired degree of fineness by the joint action of centrifugal force and of air compressed to a greater or less degree either by the action of the machine itself or from an air-compressor independent of the machine. When hard substances are ground between moving surfaces which are arranged close to each other, such surfaces are exposed to wear, while the space required between the surfaces prevents extreme fineness of the product. When revolving beaters are used, as in attrition and other mills, the small surfaces upon which the wear is exerted are soon destroyed, while also the fineness of the product varies, owing to the variations in intensity of the blows, or as they occur farther from or nearer to the center of motion. In my invention centrifugal power is used as the primary agent for moving the substances to be pulverized, which is aided by the air, which is more or less compressed in the ejectors by the velocity of the disk, and also currents of air from an air-compressor when dust of superior fineness is required.

For this purpose my invention consists, essentially, of a revolving disk secured to a horizontal shaft, said disk being provided at its periphery with funnel-shaped ejectors, through which the material to be pulverized is made to pass with great velocity, and then impacted against the inner circumference of a fixed inclosing-case, which inner circumference is provided with projections. The material is fed to the interior of the machine by a suitable hopper and discharged from the same by means of adjustable valves. When compressed air is used, it is conducted through a channel in the hollow driving-shaft and radial conducting-tubes to an intermediate space be-

tween the ejectors and smaller interior funnels, so as to assist in the ejection of the substances and reduce them thereby to a higher degree of fineness than is possible without the aid of compressed air.

In the accompanying drawings, which fully illustrate my invention, Figure 1 is a vertical transverse section of my improved pulverizing-machine worked with compressed air supplied from an exterior source. Figs. 2 and 3 are side and end elevations of the machine shown in Fig. 1. Fig. 4 is a transverse section through the apparatus shown in Fig. 1; and Fig. 5 is an enlarged view of detachable projections *f*, bolted to the peripheral flanges of the casing.

Similar letters of reference indicate corresponding parts.

Referring to the drawings, A represents a vertical disk, the thickness of which decreases slightly from the center toward the circumference, and which is secured by a strong center hub, A', to a horizontal revolving shaft, B, supported in bearings of an upright standard or standards, C. The disk A is provided at its circumference with a number of tooth-shaped projections, *a*, which are concave at one side and convex at the other side, and provided with holes for the passage of the rivets or clamping screw-bolts *a'*, by which the funnel-shaped ejectors E are secured to the projections *a*. The ejectors E are so attached to the projections *a* that the edges of their widest portions or mouths are located in radial lines drawn from the center to the inner ends of the concave edges of the projections *a* of the disk A. The funnel-shaped ejectors E are then curved from the radial mouths in outward direction, and provided at the outer ends of their shorter side walls with discharge-openings *e e*, so that the substances which are taken up by the ejectors during the revolution of the disk are thrown with great velocity through the small openings *e* of the ejectors and impelled against the corrugated inner circumference of the cylindrical inclosing-casing F. These ejectors have an exterior and an interior shell, forming a space between them for free passage of compressed air, and are secured to the disk by

means of flanges *b* and bolts through the holes *a' a'*. The casing *F* is provided with an annular bulge that corresponds to the shape of the funnel-shaped ejectors *E*, as shown in Fig. 1. 5 The projections *f* of the casing *F* are made with inclined sides, and preferably of hardened steel, they being so arranged that when one side—which has been exposed to wear by impact with the materials to be pulverized—is worn 10 out the sections can be reversed, and thereby the other side exposed to the impact of the material, whereby both sides may be fully utilized. The materials to be pulverized are fed through a hopper, *F'*, at one or both sides of 15 the inclosing-casing *F*, directly to the funnel-shaped ejectors *E*, and are thrown by the same, as they are rotated with the disk *A* at a high degree of speed by centrifugal action, through the end openings, *e e*, against the reducing projections *f*. The gradually-diminishing width of the funnel-shaped ejectors *E* and the high speed at which they are rotated cause the air to be forced through with considerable pressure, which assists the action of the centrifugal force 20 and hurls the materials with considerable force against the projections, so that they are reduced to a high degree of fineness by impact therewith. As each particle of the material is rapidly taken up and passed again and again 25 through the ejectors, it is impacted a great number of times until the required degree of fineness is imparted, when it is drawn off through suitable discharge-openings and adjustable valves *F''* at the lower part of the casing *F*, and through suitable conductors to settling drums or chambers, as customary in pulverizing-machines. The discharge-openings and valves *F''* are arranged in both sides of the casing *F*, the valves being hinged at one end 30 to the casing and arranged to open more or less, so as to assist in regulating the proper degree of fineness to which the materials are to be reduced. The larger the discharge-openings the greater is the degree of fineness to 35 which the materials are reduced before they are conducted off.

When the machine is intended to be used for pulverizing ores and other substances of a mineral nature, the force of impact that is imparted to the materials by the joint action of the centrifugal force and the velocity of the air passing through the funnel-shaped ejectors is in most cases sufficient to reduce them to the required degree of fineness. Whenever a 50 greater degree of fineness is desired—as, for instance, in pulverizing cereals or similar substances—the joint action of the two forces described is not sufficient, and it is necessary to introduce to the interior of the machine compressed air of a suitable degree of pressure 55 from an air-compressor of any approved construction or from any other exterior source of supply. For this purpose the compressed air is conducted from the compressing-machine to a receiver, *G*, at one end of the driving-shaft *B*, then through a central channel, *g*, of the

same and through radial perforations of the shaft *B* into an annular space, *g'*, in the hub *A'* of the disk *A*, and from said annular space *g'*, by radial conducting-tubes *g'' g''* at both sides 70 of the disk *A*, to the base of the ejector *E*, where the air is delivered into a narrow space formed between the outer shell of the ejector *E'*, of corresponding shape, the terminal opening of which is at a short distance from the 75 discharge-opening of the outer shell, *E*, while the mouth of the same is secured by an exterior overlapping flange to the mouth of the outer shell, as shown clearly in detail in Fig. 4. In this case the compressed air supplied 80 from the air-compressor to the space between the inner and outer shells of the ejectors throws the material, which is conducted along the interior shell, *E'*, into the path of the compressed air, with highly-increased force against the 85 small projections at the inner circumference of the casing *F*. The force of the compressed air is thus employed jointly with the action of centrifugal power for the reduction of the materials, which can thereby be pulverized to any 90 desired degree of fineness in an effective and economical manner.

Having thus described my invention, I claim as new and desire to secure by Letters Patent—

1. The combination of an inclosing-casing, 95 means for supplying the materials, means for discharging them when pulverized, a revolving disk having curved funnel-shaped ejectors applied thereto, composed of inner and outer shells of corresponding shapes, with air-spaces 100 between them, and means whereby compressed air is conducted to said spaces between the outer and inner shells of the ejectors, substantially as described.

2. A pulverizing-machine having a horizontal rotary shaft provided with a longitudinal air-channel, an air-receiver connected to the end of said shaft, a disk having an annular space in its hub, radial air-conducting tubes projecting from said annular spaces, ejectors 110 composed of inner and outer shells, having air-spaces between them connected with said air-tubes, whereby currents of compressed air are made to impinge currents of dust and air at the discharge-orifices of the ejectors, and a 115 rim or casing surrounding said disk, substantially as described.

3. A pulverizing-machine having a rotary disk, an inclosing-casing provided with projections on its inner circumference, means for admitting and means for discharging the material, an ejector composed of an outer and an inner shell, which form an air-channel between them, a compressed-air receiver, and means for conducting air from said receiver to and 120 through the air-channel of the ejector, whereby the compressed air is made to impinge a current of mingled air and dust which passes through the inner channel of the ejector and against the projections, substantially as described.

4. A pulverizing-machine, including the

- casing, having a horizontal rotary shaft provided with a longitudinal air-channel, an air-receiver at one end of the shaft, a disk having an annular space in its hub, radial air-conducting tubes projecting from said annular space, ejectors composed of outer and inner shells, forming an air-channel between them, and flanges *b*, provided with bolt-holes, substantially as described.
- 10 5. In a pulverizing-machine, an ejector composed of an inner and an outer shell, with an air-channel between them, said ejector having a funnel-shaped mouth and a discharge-nozzle at an angle thereto, the outer shell being provided
- 15 near the mouth on the side opposite the nozzle with a tube adapted to connect with an air-pipe, substantially as described.
6. In a pulverizing-machine, an ejector having a funnel-shaped mouth and a discharge-nozzle at an angle thereto, composed of an inner and an outer shell, with an air-space between them, the outer shell being constructed with a flange whereby the device may be attached to the disk, substantially as described.
- 20
- In testimony that I claim the foregoing as my invention I have signed my name in presence of two subscribing witnesses.
